(57) **CLAIM**

The ornamental design for an optical device reticle, as shown and described.

DESCRIPTION

FIG. 1 is a view of an optical sight reticle for an optical device, as viewed through an eyepiece end of the optical device; and, FIG. 2 is a perspective view showing an environment of use for the reticle of FIG. 1.

In FIGS. 1-2, the dashed lines indicate environmental features that form no part of the claimed invention.
